United States Patent Office.

JAMES INGRAM, OF NEW YORK, N. Y.

Letters Patent No. 61,835, dated February 5, 1867.

IMPROVEMENT IN HOISTING MACHINES FOR CELLARS.

The Schedule referred to in these Letters Patent and making part of the same.

TO ALL WHOM IT MAY CONCERN:

Be it known that I, JAMES INGRAM, of the city and State of New York, have invented, made, and applied to use a certain new and useful Improvement in Hoisting Machines for Cellars; and I do hereby declare the following to be a full, clear, and exact description of the said invention, reference being had to the annexed drawing, making part of this specification, wherein—

Figure 1 is an elevation of my said hoisting machine; and

Figure 2 is a vertical section of the same at right angles to fig. 1.

Similar marks of reference denote the same parts.

Hoisting machines have heretofore been made for the cellars of stores and warehouses, but they are expensive and not adapted to use in dwellings by servants, and difficulty is often experienced in carrying up ashes out of cellars and in taking down provisions.

The object of my invention is to provide for the speedy raising or lowering of any article, such as provisions, barrels of ashes, &c., from or to the cellars of dwellings, without the cumbersome and dangerous mechanism heretofore employed for stores and warehouses, my mechanism being adapted to remain stationary at any point to which the article may be raised or lowered without the use of pawls, levers, or any friction clamps heretofore employed.

The nature of my said invention consists in a pair of screws combined with a sustaining frame, and actuating gearing arranged so as to be actuated by a crank-handle and raise or lower a platform, the whole being fitted in such a manner that it is adapted to use in dwellings by the most inexperienced hands.

In the drawing, *a* is a frame connecting with the upper ends of the guide-bars *b b*, which, at the bottom end, are formed as or attached to the legs *c c*, that are fastened into a flagstone or other support at the bottom of a shallow pit below the level of the cellar floor *d*. *e e* are screw-shafts sustained by steps at the top and bottom, said screws being parallel to the guide-bars *b b*, and having at their lower ends bevel-gears, *f*, taking similar gears, *g*, upon the cross-shaft *h*, that is driven by mitre or bevel gears upon the shaft *i*, that is provided with a crank or handle, *k*, for turning it with. *l* is a platform guided by the bars *b b*, and having nuts taking the screws *e e*.

It will now be evident that by rotating the handle *k* the platform *l* can be raised or lowered together with any article placed upon it, and that it will remain in any position at which it may be placed; and when lowered entirely down, said platform comes level with the cellar floor, or nearly so, the gearing and shaft being in the pit below it. The ends of the platform *l*, that set against the sides of the bars *b*, may be made sufficiently wide to prevent the platform tipping or causing the nuts to bind or bending the screws in consequence of the weights being placed upon one side or edge of the platform *l*; thus said bars *b b* guide the platform, prevent the screws bending, and connect the top and bottom bearings for said screws.

What I claim, and desire to secure by Letters Patent, is—

The arrangement of the shaft *h*, gears and handle for rotating the screws *e e*, in combination with the guide-bars *b b* and platform *l*, as set forth, to form a hoisting machine for cellars or buildings, as specified.

In witness whereof I have hereunto set my signature this twenty-first day of March, 1866.

JAMES INGRAM.
